UNITED STATES PATENT OFFICE.

HANS M. CLEMMENSEN, OF HOUSTON, MINNESOTA.

FUEL-HEATER.

1,318,265.

Specification of Letters Patent.

Patented Oct. 7, 1919.

Application filed May 8, 1915. Serial No. 26,839.

To all whom it may concern:

Be it known that I, HANS M. CLEMMENSEN, a citizen of the United States, residing at Houston, in the county of Houston and 5 State of Minnesota, have invented certain new and useful Improvements in Fuel-Heaters, of which the following is a specification.

This invention relates to attachments for 10 hydrocarbon engines and the object of the same is to provide a simple and efficient device for heating the fuel used by hydrocarbon engines.

Another object of this invention is to provide a means for heating the fuel of hydrocarbon engines in which the water used for cooling the engine is the agency by which the fuel is heated.

A still further object of this invention is 20 to provide a device as above set forth that is so constructed and the parts thereof so arranged that, if for any reason, it is so desired, the water used in cooling the engine can be so directed as to follow its 25 ordinary path, that is, from the engine to the radiator and return.

A still further object of this invention is to provide a heating device for fuel for hydrocarbon engines that is simple in construction, efficient in operation, and consists of a minimum number of parts.

With these and other objects in view, this invention consists of certain novel constructions, combinations and arrangement of 35 parts, as will be hereinafter fully described and claimed.

In the accompanying drawings:—

Figure 1 is a view in elevation of an engine, and a fuel supply tank, the same being 40 equipped with this improved heating device;

Fig. 2 is a longitudinal sectional view of that portion of the device that engages the fuel pipe and a portion of the water feeding 45 pipes shown in elevation.

Referring to the parts by reference numerals, the pipe through which the fuel passes from the supply tank to the carbureter is designated by the numeral 10 and a cylinder 50 11 is secured on the same, preferably adjacent the carbureter. This cylinder has alined openings formed in the heads 12 thereof and collars 13 are formed integrally with the heads 12 at the alined openings, 55 these alined openings being adapted to receive the pipe 10, and suitable sleeves 14 are

threaded on the collars 13 so as to form an efficient liquid tight connection between the pipe 10 and the cylinder 11.

Means is provided in connection with this 60 cylinder 11 for providing for the flow of water through the same and thus bringing the water into contact with the fuel pipe 10. A pair of pipes 15 and 16 are connected with

this cylinder 11, the same being inlet and 65 outlet pipes respectively and cocks 17 are provided to shut off the flow of water into the cylinder when so desired. An auxiliary tributary 18 is secured to the extensions

19 and 20 on the pipes 15 and 16 respectively 70 by means of the nuts 21, the same forming a by pass. A cock 22 is provided in this auxiliary tributary 18 and normally is closed. The pipe 15 as is clearly shown in

Fig. 1 is in communication with the water 75 jackets of the engine to which the device is applied and the pipe 11 is in communication with the radiator so that the water after being partially heated by passing through the water jackets of the engine is fed into 80

the cylinder 11 by means of the pipe 15 and thus comes into contact with a portion of the pipe 10 and thereby heats the fuel contained in the pipe and as is indicated by the arrows in Fig. 2, the water flows out 85

through the pipe 16 to the radiator for cooling. This device by heating the fuel, in most instances gasoline, not only prevents the fuel from freezing in cold weather but also provides for the fuel being fed to the 90 carbureter in a partially heated state and thus efficiently aids in the forming of the charge. If, for any reason, it is not wished

to feed the the water into the cylinder 11, the cocks 17 can be closed and the cock 22 in 95 the auxiliary tributary 18 opened and the water will flow through the pipes 15, 18 and 16 to the radiator.

A drain cock 23 is provided in the cylinder 11 for an obvious purpose. 100

It is obvious that minor changes may be made in the form and construction of this invention without departing from the material parts thereof. It is therefore not wished to confine the invention to the exact 105 form herein shown and described, but it is wished to include all such as properly come within the scope claimed.

What is claimed is:

In a device of the class described, the combination of a fuel supply pipe of an engine, 110 an elongated cylinder having heads pro-

vided with collars thereon, said supply pipe passing through said cylinder and collars, sleeves carried upon said collars for forming a liquid tight joint at each end of the 5 cylinder, parallel pipes connected to said cylinder adjacent the ends thereof one of said last mentioned pipes being adapted to be connected to the water jacket of an engine and the remaining pipe being adapted to be 10 connected to the radiator of such engine, an extension formed on each of the parallel pipes, said extensions being in horizontal alinement with each other, a tributary pipe having nuts on its end portions, said nuts 15 also engaging said extensions for holding the tributary pipe upon said parallel pipes, and also parallel to said cylinder, a cock

carried by said tributary pipe intermediate the ends thereof, and cocks carried by said parallel pipes at points between the extensions thereof and said cylinder, whereby the cocks may be adjusted to permit heated water to pass from the jacket of an engine, through said parallel pipes and said cylinder for heating the supply pipe, or the cocks 20 may be adjusted for causing the water to flow out around through the parallel and tributary pipes.

In testimony whereof I affix my signature in presence of two witnesses.

HANS M. CLEMMENSEN.
